UNITED STATES PATENT OFFICE.

TIMOTHY F. WARD, OF EARLEYS, NORTH CAROLINA.

TIRE TOOL.

Application filed October 29, 1923. Serial No. 671,412.

To all whom it may concern:

Be it known that I, TIMOTHY F. WARD, a citizen of the United States, residing at

Earleys, in the county of Hertford and 5 State of North Carolina, have invented certain new and useful Improvements in Tire Tools, of which the following is a specification.

This invention relates to tools for expanding or collapsing wheel rims, especially 10 split rims used with pneumatic tires on automobiles, the object being to provide an improved and simple device for the purpose stated, having various advantages of construction and operation as will be more fully 15 apparent from the following description.

I am aware that tools for this purpose have heretofore been used or proposed, which are attended with certain defects intended 20 to be remedied by the present invention.

One of these defects is that rocking grippers or jaws are used which, when pressure is applied, tend to bend or buckle the rim, so that when the ends of the rim are drawn 25 toward each other they have a tendency, in consequence of the buckling action of the grippers, to bend or flare the ends outwardly or distort the true circle, so that it is difficult to lap the ends. And also when the 30 screw pressure is applied to expand the rim the tendency is to buckle the ends inwardly so that it is difficult to meet them in proper relation, without straining the rim by other tools or by hand.

35 A further defect of such tools is that in order to obtain the proper leverage the tools have to be made so long or large that the rim is gripped too far from the ends, or joint, and the tool is inconvenient to 40 carry. By means of the present invention the rim can be gripped quite near its ends, and the tool occupies but little space so that it may readily be carried in the tool box or pocket of an automobile.

45 Also certain rims have lugs, veins, or projections on the inside, and a tool employing an ordinary straight faced gripping jaw cannot be used where said projections interfere. The present invention provides a U-shaped 50 gripping jaw, the branches or arms of which grip the rim near its edge, outside of such lugs, veins, or projections.

Furthermore, the invention provides an improved manner of connecting the gripper 55 hooks to the body by a special headed pin so that they automatically take hold, with-

out the use of threaded bolts and nuts which will become battered and rusty, and rendered useless.

One form of the invention is illustrated 60 in the accompanying drawings, in which Fig. 1 is a side elevation of a portion of a rim showing the tool applied thereto. Fig. 2 is a plan view of one end of the tool. Fig. 3 is a section on the line 3—3 of Fig. 1. 65 Figs. 4 and 5 are details showing the hook connection.

In the drawing, 6 indicates a section of a split rim, across the joint of which the tool is applied. The tool includes a screw 7 70 threaded right and left at opposite ends and provided at the middle with a hand wheel 8 which may have lugs 9 to which a bar can be applied if desired, to turn the screw. Each end of the screw is threaded into a 75 yoke 10 the opposite arms 11 of which are provided at their ends with outwardly projecting pivots 12 which engage in the sides of a U-shaped cam piece or gripper 13, the engagement being effected at the inside 80 of the arms or branches of the cam piece between which the arms of the yoke project. A pair of grips or hooks 14 are connected to the outer side of the arms of the cam piece, by means of a cross bolt or pin 15 each 85 end of which is provided with an enlarged conical head 16. The holes in the hooks 14 thru which the pin 15 extends are elongated, as indicated at 17, and countersunk as shown at 18, so that a universal connection is formed, and when not under tension, the hooks 14 can be leaned or canted laterally, or toward the heads 16 of the pin, as shown in dotted lines in Figs. 3 and 5, 90 so as to engage or disengage the outer flanges or edges of the rim, so when tension is applied, the hooks will slip laterally down the inclines of the conical heads 16 so as to adjust themselves close beside the gripper. This action is automatic with the application 100 of pressure by means of the screw, and the use of a hand nut to effect the engagement is made unnecessary. Also, since the heads 16 are larger than the holes 17, the parts 105 cannot become detached and lost after they are assembled, the head 16 being formed by a swaging or riveting action if desired.

It will be noticed that the gripping edges 19 of the cam piece 13 are formed at the outer ends of its two arms, and have a curvature corresponding approximately with that of a rim. These cam pieces are rocked, by 110

pressure applied by means of the screw, and it will be especially noticed that the pivotal connection at 12 between the yokes 11 and the grippers 13 is "inside" of the pivotal points formed by the bolts 16. This is attended with decided advantages in comparison with tools in which the screw pivot connection is in the opposite relation. Thus if the pivotal connections 12 were at the opposite side of the pivots 15 any pressure of the screw tending to separate the ends would cause the grippers to so engage the rim as to tend to bend or buckle said ends inwardly. In other words, the line of thrust of the screw would be distant from the point of application of the gripping force to the rim, and consequently there would exist a tendency to distort the rim at said point. But with the present invention, the application 20 of the screw tension is almost in line with the points at which the rim is gripped, and the gripping action of the surfaces 19 is in the same direction as the pressure of the screw, instead of in the opposite direction as 25 in the supposed case above referred to, and the gripping action is between the adjacent or directly opposite edges of the surfaces 19 and the hooks 14, with the latter engaged over the flange of the rim, instead of being 30 between diagonally opposite edges of said surfaces and hooks as in the prior art referred to above. Thus, referring to Fig. 1, if the screw is turned to expand the rim the cam pieces 13 rock outwardly or in the same 35 direction as the thrust of the screw and the rim is gripped by the inner ends or corners of the ends 19 and hold the flanges of the rim in engagement by the hooks 14, without any tendency to buckle or distort the rim, 40 and the ends of the rim when separated remain in a true circular line instead of being pinched one way or the other. So also when the screw is turned to contract the rim, the cam pieces 13 rock until they take hold, and 45 then the points of tension of the surfaces 19 against the rim are almost in direct line with the axis of the screw, so there is no tendency to buckle the rim or flare its ends outwardly as in the former constructions. The prac-

tical advantages of this are considerable, and 50 the screw can be made so short that the tool will occupy but little space and can be used on a rim quite close to the split ends thereof.

The end of one of the arms of the yoke 11 may be provided with a curved extending 55 finger 30 adapted to contact with the bend or web of the U-shaped piece 13 so that it will not reverse itself when loose, and on the opposite side the bend or back of the yoke may be flared outwardly as indicated 60 at 31 for a similar purpose.

I claim:

1. A rim tool comprising a pair of U-shaped cam pieces, rim hooks pivoted to the opposite sides of the cam pieces, and a pressure device connecting the cam pieces and pivoted thereto, the last-named pivot being located between the first-named pivot and the rim when the tool is applied to a rim whereby the rim is gripped between adjacent 65 edges of the hooks and cam pieces.

2. A tool as set forth in claim 1, said pressure device comprising a screw.

3. A tool as set forth in claim 1, said pressure device comprising a screw and a yoke on each end of the screw, the arms of the yoke being pivotally connected to the cam piece at the inside of the branches thereof.

4. A rim tool comprising a pair of U-shaped cam pieces, a pair of hooks attached to opposite sides of each cam piece, the arms of the U-shaped cam piece being presented toward the hooks, and a screw pivotally connected to the cam pieces, said pivotal connection being located nearer the ends of said arms than the pivots of the hooks, whereby the force of the screw is applied between the last-named pivot and the rim when the tool is applied to the rim and the rim is gripped between adjacent edges of the hook and cam pieces.

In testimony whereof, I affix my signature in presence of two witnesses.

TIMOTHY F. WARD
